UNITED STATES PATENT OFFICE.

ALBERT C. ACKERMAN, OF BALLSTON SPA, NEW YORK.

DIE FOR MAKING GLOVE BLANKS.

Application filed October 7, 1924. Serial No. 742,167.

To all whom it may concern:

Be it known that I, ALBERT C. ACKERMAN, a citizen of the United States, residing at Ballston Spa, in the county of Saratoga and State of New York, have invented certain new and useful Improvements in Dies for Making Glove Blanks, of which the following is a specification.

This invention relates particularly to dies for cutting blanks for making gloves such as described in my application Serial No. 742,795 filed Oct. 10, 1924, in accordance with the process described in my application Serial No. 744,218, filed October 17, 1924, although in its broader aspect it may be employed for making blanks for different types of gloves or for gloves formed in a different manner.

An object of the invention is the provision of dies so arranged in gang form that a large number of blanks may be cut at a single operation with a minimum waste of material. In the illustration, five dies are arranged side by side, and by placing twenty-four thicknesses of knitted fabric on said dies and placing the whole in a press, blanks for sixty complete gloves can be cut at one operation, since each glove is formed from two parts only, and these parts duplicates.

A further object of the invention is the provision of means for attaching the dies to a supporting frame in proper relation so that each gang of dies can be readily and conveniently handled and will perform the cutting operation efficiently.

Another object of the invention is the provision of an ejector for each die so that the blanks will be prevented from sticking therein.

Another object of the invention is the construction of a die of such form that the outer sides from thumb and little finger toward the wrist will slope at an angle to the median line, thus permitting a gang of dies to be assembled with alternating dies in reverse order and thereby eliminating waste of material in cutting.

Further objects will be apparent from the following detailed description and the appended claims.

In the drawings:

Figure 1 is a top plan view of a gang of dies assembled upon a support.

Figure 2 is a front elevation of the same.

Figure 3 is a view showing certain steps in the making of the glove.

Figure 4 is an end elevation of a die.

Figure 5 is a cross section thereof.

Figure 6 is an isometric view of a die and support in disassembled form. 60

A plurality of dies A may be assembled on a base or support B as shown in Figure 1, but the construction of each die is the same whether one or more are employed. To the support B are fastened by any suitable means blocks c, c', and c'', outlining the wrist portion, and similar blocks d on the thumb side and e on the little finger side, placed at appropriate angles. There are also fastened to the base blocks f, g, h, i and k, corresponding to the thumb and fingers. All of these blocks are of the same thickness so that the material pressed down on the dies will contact evenly with them at all points. 75

A member C is fastened to the block c by screws x as indicated, while a die member C' is fastened by similar screws y to the blocks c' and e. This die member has a curved in-turned end and forms the little finger. It 80 engages the outer side of the block k. On the other side a die member C'' is fastened by screws z to the blocks c'', d and f, and has an in-turned curved end F which is extended along the inside of the block f to form the 85 cut between the thumb and index finger.

A die member G is fastened by screws v to the outside of the block g and its outer end is curved around the same. A die member H extends along both sides of the block 90 h and around its end and forms the middle finger. A die member I is fastened by a screw w to the outside of the block i and has a curved outer end contacting with the die member H. 95

When the die members are assembled, the member H fits around the block h and snugly between the blocks i and g, the members G and I are held to the blocks g and i by screws v and w respectively, the member C' is fastened to the blocks c' and e, and the member C'' is fastened to the blocks c'', d and f. 100

The construction already described is that of a single die. When a plurality of 105 dies are assembled as shown in Figure 1, if the single dies were placed side by side as might be done, this would result in a double thickness of metal where the little finger sides contact and where the thumb sides contact. It is therefore found to be more satisfactory to modify the construction slight- 110

ly. A long member L forms the little finger side of two adjacent blanks and is attached to the blocks c' by screws l . It lies between the two blocks e of adjacent forms and between the blocks c' and k , and is thus held firmly in position. The curved ends of the little fingers are formed by separate die members K fastened to the blocks k by screws l' or held in place in any other desired fashion.

Similarly the thumb side of two adjacent blanks is formed by a long member M attached to the blocks c^2 by screws m . The thumb part F then has an outer curved end M' and is fastened to the inside of the block f by screws m' . The member M passes between adjacent blocks d , and by the means described is held in proper position. In this manner any desired number of dies may be assembled, although with the tubular material usually employed, five are found preferable. By making each glove from two identical blanks and arranging the dies in reverse order, the waste of material can be reduced to a minimum.

Each complete die is provided with an ejector formed of a piece of spring metal N fastened to the base by screws n , and extending upwardly and toward the wrist portion where it has a broadened portion N' lying normally slightly above the edge of the dies. After the cutting operation, when pressure is removed, these ejectors move the blanks up to a position which facilitates their easy removal.

It will be noted that I have provided a gang die which comprises a plurality of cutting elements arranged side by side for respectively blanking out the glove body, wrist, fingers, and thumb; that the wrist portion of one cutting element is arranged intermediate the fingers of adjacent cutting elements; that the thumb portions of an adjacent pair of cutting elements are disposed against each other with their outer ends projecting in opposite directions, and that said adjacent pair of cutting elements includes a single die element for cutting the outer sides of said thumbs.

Figure 3 shows three steps in the manufacture of the glove, the view R showing two blanks as cut by the dies and then stitched by a single row of stitching. View S shows the appearance after the raw edge of the wrist has been folded and view T shows the appearance of the completed glove after it has been fulled, dried, and shaped. The method and article are more clearly and fully described in my applications above identified.

Details may be modified without in any way departing from the spirit of the invention which is to be regarded as limited only by the scope of the appended claims.

In Figure 1 the dies composing the gang

are shown as being mounted on a support which is somewhat larger than necessary and there is a considerable margin around the dies, but it should be understood that the dies may be so arranged that they will cut from material of smaller dimensions than the support B and with very little waste at either end or on either side of the dies.

I claim as my invention:

1. A gang of dies for cutting glove blanks comprising a support, a plurality of dies arranged thereon in reverse order for cutting identical blanks each suitable for front or back of the glove, a plurality of blocks on the support for each die, and a plurality of individual cutting elements for each die, each element being attached to a block, and the adjacent thumb sides of two blanks being cut by a single die element.

2. A gang of dies for cutting glove blanks comprising a support, a plurality of dies arranged thereon in reverse order for cutting identical blanks each suitable for front or back of the glove, and a plurality of individual cutting elements for each die, the adjacent little finger sides of two blanks being cut by a single die element.

3. A gang of dies for cutting glove blanks comprising a support, a plurality of dies arranged thereon in reverse order for cutting identical blanks each suitable in the form cut for front or back of the glove, and a plurality of individual cutting elements to cut the fingers and thumb of each blank, the adjacent thumb sides of two blanks being cut by a common die.

4. A die for cutting a glove blank comprising a plurality of cutting elements connected for joint operation for simultaneously blanking out the glove body, fingers and thumb of the glove, the inner portion of the cutting element for the thumb being extended diagonally inward across and below the outer cutting element for the fore-finger.

5. A gang die for cutting glove blanks, comprising a plurality of cutting elements arranged side by side for respectively blanking out the glove body, wrist, fingers, and thumb, the wrist portion of one cutting element being arranged intermediate the finger portion of adjacent cutting elements.

6. A gang die for cutting glove blanks, comprising a plurality of cutting elements arranged side by side for respectively blanking out the glove body, wrist, fingers, and thumb, the wrist portion of one cutting element being arranged intermediate the finger portion of adjacent cutting elements, and the thumb portions of an adjacent pair of cutting elements being disposed against each other with their outer ends projecting in opposite directions.

7. A gang die for cutting glove blanks, comprising a plurality of cutting elements arranged side by side for respectively blank-

ing out the glove body, wrist, fingers, and thumb, the wrist portion of one cutting element being arranged intermediate the finger portion of adjacent cutting elements, and the thumb portions of an adjacent pair of cutting elements being disposed against each other with their outer ends projecting in op-

posite directions, said adjacent pair of cutting elements including a single cutting element for cutting the outer sides of said thumbs.

In testimony whereof, I have hereunto subscribed my name.

ALBERT C. ACKERMAN.
